UNITED STATES PATENT OFFICE.

MCKEE COOPER, OF ASHEVILLE, NORTH CAROLINA.

ROTARY ENGINE.

1,332,427.

Specification of Letters Patent. Patented Mar. 2, 1920.

Application filed January 21, 1919. Serial No. 272,392.

To all whom it may concern:

Be it known that I, MCKEE COOPER, a citizen of the United States, residing at Asheville, in the county of Buncombe and 5 State of North Carolina, have invented certain new and useful Improvements in Rotary Engines, of which the following is a specification.

This invention has relation to rotary engines, and has for a primary object to improve the type of rotary engine shown in my co-pending application filed May 10, 1918, and bearing Serial No. 233,741.

A further object of the invention is to 15 provide an improved combustion chamber in place of the combustion chamber disclosed in the application above referred to whereby the combustion chamber is scavenged completely of burnt gases subsequent 20 to each operation thereby permitting the explosion of an undiluted fresh charge at each operation or cycle of operation of the machine.

A still further object of the invention is 25 to provide an improvement in my rotary engine as set forth above in which the advantages are accomplished through the medium of combustion chambers in the nature of auxiliary cylinders located above the 30 pump cylinders, and pistons operating in both cylinders and connecting in tandem fashion whereby the charge is transferred from one cylinder to the other and exploded and subsequently carried to the rotor of the 35 engine in a manner which will be obvious as the description proceeds.

A still further object of the invention is 40 to provide a form of valve to be used in the piston and other parts of my improvement whereby to secure a close and tight fitting joint when disposed in closed position and whereby to insure the uniform wear of the valve.

In addition to the foregoing, this invention 45 comprehends improvements in the details of construction and arrangement of parts, to be hereinafter described and particularly set forth in the appended claims.

In the accompanying drawings in which 50 similar and corresponding parts are designated by the same characters of reference

throughout the several views in which they appear—

Figure 1, is a view in side elevation of a rotary engine embodying my improvement. 55

Fig. 2, is a view thereof in plan.

Fig. 3, is a view partly in section taken on the line 3—3 of Fig. 2.

Fig. 4, is a similar view partly in section taken on the line 4—4 of Fig. 2. 60

Fig. 5, is a detail view in section of the combustion chamber piston.

Fig. 6, is a bottom plan view of one of the valves and.

Fig. 7 is a vertical sectional view through the rotor and casing.

Mounted on a base plate 1 are the upright cylinders 2, herein shown as four in number and cast *en bloc*. Pistons 3 reciprocate therein as shown in Fig. 3 and the connecting rods 4 lead downward to a main crank shaft which need not be illustrated. The crank shaft is continued to the rear and appears at the left of Fig. 1 at 5 where it constitutes the driving shaft, and its cranked front end rotates within the crank case illustrated at 6. Located at each side of the cylinders and extending longitudinally of the engine is a tank 8, both of which are of considerable size and strength and are closed at one end as at 9 and connected at the other by couplings 10 with a cross pipe 11 and a T-coupling 12, from whose stem the motive fluid flows through a throttle valve 13 and pipe 14 to a box 15 for use as described 85 below.

The motive fluid of my engine is the expanded gases of combustion, produced by compressing a mixture of gasoline vapor and air, and exploding it. This mixture is 90 generated in the carburetor 20, from whence it is led into the intake manifold 21, whereof a branch 22 leads to each cylinder, a check valve 23 opening toward the cylinder, being interposed at a suitable point in the branch 95 as shown in Fig. 2.

Mounted directly above each pump cylinder is a second cylinder 24, smaller in diameter than the pump cylinder, but corresponding in length thereto. The connecting rod 4 of each piston 3 is extended upwardly as at 25 through a packing gland 26 pro-

vided in the upper wall of the pump cylinder, and each extension 25 of the connecting rod carries a scavenging piston 27. An outlet is provided at the upper end of each 5 cylinder or combustion chamber 24, and said openings communicate with branches 28 which lead to transverse conduit 29 opening into the tanks 8 as shown in Fig. 2. A plurality of valves are provided in each scavenging piston 27, and the construction as 10 shown consists in providing a plurality of downwardly tapering openings 30 forming apertures for the passage of gas through the piston and also to form valve seats for 15 the conical valves 31. Each of said valves is provided at its lower end with a plurality of curved radial arms 32 which serve to limit upward movement of the valve and also for another purpose which will be presently obvious. The upper wall of each 20 pump cylinder is also apertured to provide communication between the interior of each pump cylinder and its respective combustion chamber located thereabove, said openings 25 being indicated at 33 in Fig. 3. Operating in these openings 33 are conical valves 34 of the construction just described, said valves, in a manner similar to the valves 31 opening upward. Each cylinder 24 is perforated at one side to admit of the introduction of spark plug 25 as shown in Fig. 3.

The rotary portion of my engine is shown to the left of Fig. 1 and for a detailed description thereof the reader is referred to my co-pending application mentioned above. At any rate, the casing 36 contains a rotor of the type provided with its radiating blades or buckets which receive the impact of gas delivered through pipes 37 entering nozzles 38, said pipes 37 radiating from the distributing box 15. The rotor within the casing is mounted directly upon and keyed to the shaft 5 so that the pump and rotor operate in unison.

In operation, upon each downward stroke of a piston 3, a charge of gasoline vapor and air is drawn from the carburetor through the branches 21 into the upper end of the pump cylinder and upon the succeeding upward stroke of said piston the charge is forced through the openings 33 into the combustion chamber directly thereabove, said valves 34 opening upward to permit the passage of the charge. It will be obvious that the scavenging piston 27 being connected to the piston 3 also moves upwardly and the capacity of the combustion chamber is thus uniformly increased to receive the charge as it is received in the combustion chamber. However, it will be noted that the capacity of the combustion chamber is less than that of the pump cylinder and consequently the charge is compressed in the combustion chamber. At the proper moment a

mechanism not shown is operated to cause 65 a spark at the spark plug 35 which ignites the charge within the combustion chamber, causing the combustion and expansion of the gases therein. The next succeeding downward movement of the piston 3 and its 70 scavenging piston 27 obviously causes the transferal of the gases from beneath the piston 27 to the upper end of the combustion chamber above said piston, and the next succeeding upward stroke of said piston 27 7 drives the gases from the combustion chamber through the conduits 28 and 29 into the tanks 8 which serve as a temporary place of storage for the gases from which they are ultimately conveyed through the 80 branches 11 and 14 into the distributing box 15 and through the nozzles 38 into the rotor casing 36, thereby setting up rotation in the rotor which is communicated through the crank shaft to the pump pistons, and 85 the operation of the engine is carried on in the manner set forth above. It will be obvious that owing to the operation of the scavenging pistons 27 the burnt gases are transferred completely from one side of the 90 piston to the other, thereby cleaning the combustion chamber for the introduction of the next charge. In this manner the incoming charge is undiluted and hence a greater amount of power can be obtained 95 by means of this improvement than would be possible with the form of combustion chamber shown in my co-pending application.

It will also be obvious that this scavenging piston and co-operating parts may be applied to internal combustion engines of various type with considerable advantage. It is desirable to note that owing to the provision of the radiating blades 32 of the 105 valve described above, each valve, when lifted has imparted thereto a slight rotary motion which causes the valve to contact its seat at different points and consequently the wear upon the valve is rendered more uniform.

While I have illustrated and described my invention with some degree of particularity, I realize that in practice various alterations therein may be made. I therefore reserve 110 the right and privilege of changing the form of the details of construction or otherwise altering the arrangement of the correlated parts without departing from the spirit of the invention or the scope of the 120 appended claims.

Having thus described my invention, what I claim as new and desire to secure by United States Letters Patent is:

1. A device as specified including a series 125 of cylinders, each having inlet and outlet ports, a piston movable in the cylinders to draw a combustible mixture through the

1,332,237
5
inlet port and to expel it through the outlet port, a series of auxiliary cylinders communicating with the outlet port of the main cylinders to receive the combustible mixture, and being relatively smaller than the latter to cause compression of said mixture in the auxiliary cylinders, ignition means associated with said auxiliary cylinders to ignite the mixture, and pistons mounted in the auxiliary cylinders, and in connection with the pistons in the main cylinders, to force the products of combustion from said auxiliary cylinders.

6
5 2. A device as specified including main and auxiliary cylinders in communication with each other, pistons mounted in said cylinders and connected together so as to be simultaneously operable, said main cylinders adapted to receive the combustible mixture and to force the same into the auxiliary cylinders, which latter are relatively smaller than the main cylinders to effect compression of the mixture, ignition means in said auxiliary cylinders for igniting the mixture, conduits for conveying the products of combustion from said auxiliary cylinders, and a rotor remote from said cylinders and in communication with said conduits to be operated by the products exhausted through said conduits.

33
35 3. A prime mover including a rotor, a series of cylinders, pistons movable in said cylinders and operated from said rotor, an auxiliary cylinder in communication with each of said first mentioned cylinders, valves controlling communication between the primary and auxiliary cylinders of each pair, a piston in each auxiliary cylinder directly connected to its respective main piston, a tank, a connection between said auxiliary cylinders and tank, means for igniting a charge of vapor in the auxiliary cylinders, valves in the auxiliary pistons, and nozzles directed upon the rotor and fed from said tank.

45
40 4. A prime mover including a rotor, a pump cylinder, a piston movable therein operated by the rotor, an auxiliary cylinder in communication with the pump cylinder, check valves controlling said communication, carburetion means in communication

55
with the pump cylinder, a piston movable in the auxiliary cylinder, said piston having passages therethrough, valves in said passages, means for igniting the vapor in 55 the auxiliary cylinder, a tank in communication with the auxiliary cylinder, and nozzles directed upon said rotor and fed from said tank.

60
65 5. A prime mover including a rotor, a cylinder, a piston movable in said cylinder and operated by said rotor, an auxiliary cylinder in communication with the pump cylinder, a piston in said auxiliary cylinder, a rod connecting both of said pistons, check 65 valves controlling communication between said cylinders, an auxiliary piston having transverse openings, valves in said openings, means for introducing vapor into the pump cylinder, means for igniting the vapor in 70 the auxiliary cylinder, a tank, a communication between the auxiliary cylinder and tank, and nozzles directed upon the rotor and fed from the tank.

75
80 6. A device as specified including cylinders and corresponding pistons arranged in tandem, one cylinder of each tandem being larger than the other and functioning as a pump, the smaller cylinder being equipped with ignition means and constituting the 80 combustion chamber the products of combustion being forced from said chamber by the piston therein substantially as described.

85
90 7. A device as specified including cylinders and corresponding pistons arranged in tandem, one cylinder of each tandem being larger than the other and functioning as a pump, the smaller cylinder being equipped with ignition means and constituting a combustion chamber, the products of combustion being forced from said chamber by the piston therein, a rotor, and conduits conveying the products of combustion from the combustion chamber to the rotor for impelling the latter.

95
In testimony whereof I affix my signature in presence of two witnesses.

McKEE COOPER.
